UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,846, dated April 4, 1882.

Application filed January 26, 1882. Term of patent 3½ years.

To all whom it may concern:

Be it known that I, ARTHUR L. HALLIDAY, of New York, in the county and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

The figure A has a cross in its center, with a projection from one end, said cross and projection being surrounded by an irregular band.

The figure A' is very similar to A, but is modified in some details.

The figure B somewhat resembles a three-leaved clover.

The figure C consists of flowers and leaf-like figures growing upon a central stem, one projecting stem having a figure resembling a bunch of leaves extending from it.

The figure C' is similar to the figure C, but has a number of changes in its details.

The figure D consists of a central rosette, with leaf-like figures projecting from it.

The figure E consists of three circular figures somewhat resembling spiders.

The figure F somewhat resembles an oak-leaf.

The figure G resembles a branch.

The figure H consists of a central rosette, with crosses, stems, and leaf-like projections outside of it.

The figure J consists of three spider-like circular figures somewhat resembling the figure E.

The figure K consists of a large leaf-like figure.

The backgrounds of these figures and of other minor ornaments consist of various small figures regularly repeated. Thus the background L consists of a series of small squares, the background M of a series of lines with little dotted circles interspersed. The background N consists of a series of various rectangular figures, and the background O of a series of oblong parallelograms. The background P consists of a series of dagger-like figures, and the background Q of a series of broken squares.

I claim—

1. The design for carpet, consisting of the figure C, substantially as shown.
2. The design for carpet, consisting of the figure E, substantially as shown.
3. The design for carpet, consisting of the figure G, substantially as shown.
4. The design for carpet, consisting of the figure K, substantially as shown.
5. The design for carpet, consisting of the background L, substantially as shown.
6. The design for carpet, consisting of the background M, substantially as shown.
7. The design for carpet, consisting of the background N, substantially as shown.
8. The design for carpet, consisting of the background O, substantially as shown.
9. The design for carpet, consisting of the background P, substantially as shown.
10. The design for carpet, consisting of the figures A A' B C C' D E F G H J K and backgrounds L M N O P Q, substantially as shown.

ARTHUR L. HALLIDAY.
